UNITED STATES PATENT OFFICE.

JOHN REGAN, OF NEW BEDFORD, MASSACHUSETTS, ASSIGNOR TO CROMPTON & KNOWLES LOOM WORKS, OF WORCESTER, MASSACHUSETTS, A CORPORATION OF MASSACHUSETTS.

STOPPING MECHANISM FOR KNITTING MACHINES.

Application filed November 25, 1924. Serial No. 752,208.

This invention relates to knitting machines of the type used particularly for producing flat knitted fabric. In such machines it is necessary that the machine be stopped 5 promptly upon the breakage or slackness of any of the yarn threads.

It is the object of my invention to provide an improved stopping mechanism by which this result may be accomplished accurately 10 and reliably. To the attainment of this object, I have provided certain arrangements and combinations of parts which will be hereinafter described and more particularly pointed out in the appended claims.

15 A preferred form of the invention is shown in the drawings in which—

Fig. 1 is an end elevation of a knitting machine having my improved stop motion applied thereto;

20 Fig. 2 is a detail sectional plan view, taken along the line 2—2 in Fig. 1;

Fig. 3 is an end elevation of parts of the stopping mechanism;

25 Fig. 4 is a sectional end elevation, looking in the opposite direction from Fig. 1; and

Fig. 5 is a view similar to Fig. 4 but showing the parts in a different position.

Referring to the drawings, I have shown a knitting machine having a frame 10 which 30 supports a pair of yarn rolls 11. Each yarn roll 11 is provided with a tension roll or whip roll 12 which is yieldingly pressed outward as indicated in the drawings. The yarn threads pass from the tension rolls 12 35 to the knitting mechanism M which may be of any usual construction and in itself forms no part of my present invention.

My improved stopping mechanism is 40 preferably formed in units mounted at each side of the machine, the two units of the stopping mechanism being connected together and operating as a single mechanism.

I will first describe the primary unit of 45 the stopping mechanism shown at the right in Fig. 1 and at the left in Figs. 4 and 5.

The stopping mechanism is mounted upon frame ends or heads 15 each adjustable along a rod 16. Each rod 16 has an offset vertical portion 17 fixed therewith and held 50 for vertical adjustment in a bracket 18. Cross bars 20 extend between the heads 15 and act as guides for a plurality of drop wires 21. These wires are preferably forked

at their lower ends and rest upon the separate yarn threads Y.

55 Each drop wire is provided with an elongated slot in its upper portion through which extends a vibrator bar 22 of non-circular cross-section. When the drop wire is in the raised position shown at the left in Fig. 4, the vibrator bar 22 is free to oscillate in the wide lower portion of the drop wire slot, but when a yarn thread breaks or becomes 60 too slack and permits its drop wire to fall, the vibrator bar 22 is caught in the narrow 65 upper end of the slot and is thus prevented from oscillation.

The vibrator bar 22 is rotatably mounted and is connected at one end to a bell crank 24 which is yieldingly connected by the 70 U-shaped link 25 to a rocker arm or lever 26. The link 25 is slidable through a stud 27 in the end of the lever 26 and is provided with collars 28 and 29 and a spring 30. The lever 26 thus moves the link 25 and bell 75 crank 24 positively upward but pushes them yieldingly downward, so that the bell crank 24 may remain in raised position if the vibrator bar is caught in the narrow portion of a drop wire slot. In this case, the 80 lever 26 merely compresses the spring 30 along the link 25.

The lever 26 is pivoted at 31 on the head 15 and has a connection through a link 33 (Fig. 1) to a lever 34, regularly oscillated 85 by a cam 35. The throw of the lever 26 may be varied by adjusting the point of connection of the link 33 to the lever 26 or to the lever 34.

The lever 26 also has a depending hook-shaped projection 36 positioned to be at times 90 engaged by a latch 37 pivoted at 38 on a knock-off arm 39 which swings about the fixed pivot 31 previously described. The latch 37 has a rearward projection 40 to 95 which is adjustably secured a finger 41 positioned for engagement by the depending lower portion 24^a of the bell crank 24.

Under normal conditions, as the bell crank 24 is forced downward by the lever 26 and yielding link 25, the lower end of the bell crank will engage the finger 41, thus depressing the latch 37 below the path of the hook 36. The knock-off arm 39 then remains in its normal position.

100 If, however, a drop wire has fallen, the 105

vibrator bar 22 is held fast and the bell crank 24 fails to depress the pawl 37, which is thereafter engaged by the hook 36 and forced to the right, as shown in Fig. 5, 5 swinging the knock-off lever 39 also to the right. A rod 42 (Fig. 3) is fixed in the knock-off lever 39 and extends downward as indicated in Fig. 1. At its lower end it is connected by a link 43 to a bell crank 44 10 (Fig. 2) having a rod or arm 45 positioned to engage an arm 46 on a sliding shaft 47. The shaft 47 carries a fork 48 engaging a swinging arm 49 connected to open and close a switch 50 by which the driving mechanism 15 of the machine is controlled. When the rod 42 is swung to the left, as indicated in Fig. 1, by movement of the knock-off lever 39, it acts through the bell crank 44 and arm 45 to slide the shaft 47 axially and open the 20 switch 50.

The stopping mechanism unit shown at the right in Figs. 4 and 5 is similar in construction and operation to the stopping mechanism previously described. A vibrator bar 60 is mounted for oscillating movement by a swinging arm 61 which is connected by an adjustable link 62 to the depending arm 24^a of the bell crank or lever 25 24 on the primary stop motion unit previously described. The vibrator bars 22 and 60 thus move in unison and the stopping mechanism becomes operative if the free movement of either vibrator bar is prevented.

Having thus described my invention, it 35 will be seen that I have provided a stopping mechanism for a knitting machine so constructed that it will control the yarn threads on the two opposite sides of a knitting machine and that the breakage of a single 40

thread on either yarn roll will occasion prompt stopping of the machine. It will also be seen that I have avoided duplication of operating parts and that my improved stopping mechanism is effective and reliable in its operation. 45

Having thus described my invention and the advantages thereof I do not wish to be limited to the details herein disclosed otherwise than as set forth in the claims, but 50 what I claim is:—

1. In a knitting machine, a primary stop motion unit at one side of the machine comprising drop wires, a vibrator bar, actuating mechanism therefor, and knock-off devices, and a second unit at the opposite side of the machine comprising drop wires, a 55 vibrator bar, and a rod directly connecting said two bars.

2. In a knitting machine having a large 60 number of yarn threads, a pair of oppositely disposed yarn rolls on which said yarn threads are wound, a tension roll for each 65 yarn roll and each providing tension for all of the yarn threads on its associated yarn roll, a separate series of drop wires for the yarn threads on each yarn roll engaging said threads between the yarn roll and its associated tension roll, a separate 70 vibrator bar for each series of wires, a complete stopping mechanism unit for one series of drop wires, a partial stopping mechanism unit for the other series of drop wires, operative connections between said units, comprising a rod directly connecting said vibrator bars and stopping devices directly controlled from said first unit. 75

In testimony whereof I have hereunto affixed my signature.

JOHN REGAN.
